UNITED STATES PATENT OFFICE.

WILLIAM H. DE BUSK, OF CHICAGO, ILLINOIS, ASSIGNOR TO THE P. & M. COMPANY, OF CHICAGO, ILLINOIS, A CORPORATION OF ILLINOIS.

RAIL ANCHOR.

Application filed August 27, 1923. Serial No. 659,584.

To all whom it may concern:

Be it known that I, WILLIAM H. DE BUSK, a citizen of the United States, residing at Chicago, in the county of Cook and State of Illinois, have invented certain new and useful Improvements in Rail Anchors, of which the following is a specification.

My invention relates to rail anchors for preventing the longitudinal creeping of rail-road rails, and has for its principal object the provision of a new and improved combination of parts, by which an anchor may be tightened in position on a rail.

My invention relates more particularly to the type of anchor shown in my application for Letters Patent of the United States, Serial No. 622,956, filed March 5, 1923, of which this application is a continuation in part.

It is one of the objects of my invention to provide a construction of this type in which the tightening of the anchor upon its transverse movement with respect to the rail is effected both by reason of a differential movement of the jaws or arms at opposite sides of the rail, and also by reason of a differential leverage of the arms at opposite sides of the rail.

It is another object of my invention to provide an improved form of device for causing differential movement of the arms or jaws at the opposite sides.

It is still another object of my invention to improve devices of this type in sundry details hereinafter pointed out. The preferred means by which I have accomplished my several objects are illustrated in the drawing and are hereinafter specifically described. That which I believe to be new and desire to cover by Letters Patent is set forth in the claims.

In the drawing—

Fig. 1 is a face view of one form of my improved anchor in operative position on a rail, the rail being shown in cross section with the head of the rail broken away, the normal shape of the body of the anchor from which it is distorted in its application to the rail being indicated by dotted lines.

Fig. 2 is a view similar to Fig. 1, but illustrating the use of a modified form of device for holding the anchor from loosening on the rail.

Fig. 3 is another view similar to Fig. 1,

but showing another modified form of wedge device.

Fig. 4 is a view similar to Fig. 1, but showing still another modified form of wedge device; and

Fig. 5 is a view showing the outline of the blank from which the wedge device of Fig. 4 is formed.

Referring to Fig. 1, 10 and 11 indicate the flanges at the opposite sides of a rail, and 12 indicates the web of the rail, the upper faces of the flanges 10 and 11 being sloped as is usual in connection with American railroad rails. 13 indicates the body of the anchor device, having a bearing 14 against the bottom face of the rail, and being bent inwardly at its ends to provide jaws or arms 15 and 16 adapted to press downwardly upon the upper faces of the flanges 10 and 11, such downward pressure being applied either by direct contact of the jaw with the flange or by the use of an interposed plate or wedge 17. The anchor is preferably applied to the rail closely adjacent to the cross tie 18, as is usual with devices of this type. In the construction illustrated, the plate 17 interposed between the jaw 16 and the upper face of the flange 11, is in the form of a wedge with its thicker portion disposed adjacent to the outer face of the flange. The wedge 17 is provided with a downward extension 19 at its outer edge, adapted to engage the outer face of the flange 11. As is shown by dotted lines in Fig. 1, the normal shape of the anchor device is such that the bearing 14 would normally stand at some little distance above the bottom face of the rail, in the applied position of the anchor, the arrangement being such in this regard that it is necessary to distort the anchor by moving the bearing 14 downwardly with respect to the ends of the jaws 15 and 16, against the resilient action of the bar making up the anchor device, in the application of the device to the rail.

The device of Fig. 1 is applied to the rail in the well understood manner. The jaw 16 is first applied to the flange 11, with the end of the jaw 16 adjacent to the web 12 of the rail, and the wedge 17 is inserted underneath the jaw. The anchor is then raised to bring the jaw 15 into engagement with the edge of the flange 10, whereupon the body of the anchor is driven or otherwise

forced toward the right in Fig. 1 for bringing the parts to the position shown in said figure, the wedge 17 meanwhile being held in any suitable manner in position upon the flange. It will be understood that the wedge 17 is of sufficient size longitudinally of the rail as to provide bearings at opposite sides of the body of the anchor for the desired purchase upon the wedge for holding it in position. When the end of the jaw 16 snaps into engagement with the shoulder 20 provided on the upper face of the wedge, the body portion of the anchor is, of course, prevented normally from moving again toward the left in said figure, the anchor being thus prevented from loosening on the rail.

As will be readily understood, in the application of the device to the rail, the tightening of the anchor is due in part to the fact that when the body of the device moves toward the right in Fig. 1, the arm or jaw 15 is moved upwardly upon the upper face of the flange 10, while the arm or jaw 16 and the bottom bearing 14 are moved substantially horizontally. Inasmuch as the parts are arranged and proportioned so that the device fits tightly upon the rail when first applied thereto and before the transverse movement as described, it will be understood that the transverse movement results in a distortion of the anchor, serving to tighten the device very effectively upon the rail. The shoulder 20 is to be of such a size as to serve normally for preventing disengagement of the end of the jaw 16 therefrom after such jaw has snapped into engagement therewith.

It will be understood, however, that when the anchor is to be removed from the rail, the jaw 16 can be readily moved upwardly out of engagement with the shoulder 20 by the application of upward pressure thereon.

A further tightening effect upon the transverse movement of the body of the anchor toward the right in Fig. 1, is produced by reason of the differential leverage at opposite ends of the device; that is to say, by reason of the fact that the distance between the bearing 14 and the end of the jaw 15 is considerably less than the distance between the bearing 14 and the end of the jaw 16.

The anchor device of Fig. 2 is similar to that shown in Fig. 1, by which a differential leverage is provided at opposite sides of the rail, but a different form of device is provided for preventing the loosening movement of the anchor upon the rail after its application. The form of device here shown comprises a plate 21 provided with a shoulder 22 pressed in the upper face of the plate, the arrangement being such that the effective thickness of the plate 21 is the same at the outer edge of the flange as that at

the inner edge of the plate adjacent to the web 12. The plate 21 is thus not relied upon for tightening the anchor, but only for holding the anchor against moving in the direction for loosening the anchor upon the rail.

In this construction, however, the anchor is tightened by reason of the differential leverage. As will be readily understood, in the transverse movement of the body of the anchor toward the right in Fig. 2, the end of the jaw 16 is moved downwardly substantially the same distance as the end of the jaw 15 is moved upwardly. The body of the anchor has accordingly been given a slight rocking movement in clockwise direction in said figure, during such transverse movement into operative position. It will be understood, however, that by reason of the differential leverage of the device at opposite sides of the rail, it would have been necessary for the jaw 16 to move downwardly a greater distance than the jaw 15 moved upwardly if such movement were to be effected without distortion of the device. It is, therefore, clear that upon the transverse movement the anchor is tightened, since the jaw 16 is unable to have such greater downward movement.

In Fig. 3 I have shown a modified form of wedge device 23, the same being formed of sheet metal bent into shape for providing a shoulder 24 supported by the underlying turned edge portion 25 of the metal.

In Fig. 4, I have shown still another form of wedge device 26, having a shoulder 27 supported by the underlying turned edge portion 28. The plate 26, however, does not extend to the web 12 of the rail for preventing inward movement of the wedge, as does the plate 23 of the form shown in Fig. 3, but such inward movement of the plate 26 is prevented by the use of arms or hooks 29 which engage the edge of the flange 11, the arms or hooks 29 being formed integrally with the plate 26, as is best shown in Fig. 5.

While I prefer to employ one of the constructions as illustrated in the several figures of the drawing, it will be understood that I do not wish to be restricted to the use of such constructions, except so far as the same are specifically claimed, since it is evident that many changes may be made in the details of the constructions, without departing from the spirit of my invention.

I claim:

1. A rail anchor comprising a body adapted to extend across the bottom face of a rail, jaws carried by said body and overlying the upper faces of the flanges at opposite sides of the rail, the body comprising a bearing for the bottom face of the rail located between the jaws, the parts being so arranged that the device is applicable

to a rail from one side thereof and is tightened thereon by transverse movement of the body and jaws with respect to the rail, and comprising a member interposed

5 between one jaw and the upper face of the adjacent flange and provided with a shoulder serving by engagement with the said jaw normally to prevent a reverse loosening movement of the body and the jaws on the rail, said member having a bearing on the outer edge of the adjacent flange for holding the member against movement inwardly with respect to the flange.

2. A rail anchor comprising a body 15 adapted to extend across the bottom face of a rail, jaws carried by said body and overlying the upper faces of the flanges at opposite sides of the rail, the body comprising a bearing for the bottom face of the rail located between the jaws, the parts being so arranged that the device is applicable to a rail from one side thereof, a wedge interposed between one of the jaws and the upper face of the adjacent flange 25 with the thicker portion of the wedge disposed adjacent to the outer edge of the flange, and means engaging the outer edge of said flange serving to hold the wedge from moving inwardly on the upper face 30 of the flange, the arrangement being such that when the body and jaws are moved laterally with respect to the wedge and with respect to the rail into operative position on the rail, a differential movement of the jaws is produced with respect to the rail serving to tighten the anchor on the rail.

3. A rail anchor comprising a body adapted to extend across the bottom face of a rail, jaws carried by said body and overlying the upper faces of the flanges at opposite sides of the rail, the body comprising a bearing for the bottom face of the rail located at a shorter distance from the bearing portion of one jaw on the adjacent flange than that from the bearing portion of the other jaw on the flange adjacent thereto, the parts being so arranged that the device is applicable to a rail from one side thereof, and is tightened on the rail 45 by transverse movement of the body and jaws with respect to the rail, and means serving by engagement with the end of one of the jaws normally to prevent movement of said jaw in the direction for loosening 50 on the rail.

4. A rail anchor comprising a body adapted to extend across the bottom face of a rail, jaws carried by said body and overlying the upper faces of the flanges at 60 opposite sides of the rail, the body comprising a bearing for the bottom face of the rail located at a shorter distance from the bearing portion of one jaw on the adjacent flange than that from the bearing portion 65 of the other jaw on the flange adjacent

thereto, the parts being so arranged that the device is applicable to a rail from one side thereof, and is tightened on the rail by transverse movement of the body and jaws with respect to the rail, and a plate 70 interposed between one of the jaws and the upper face of the adjacent flange and provided with a shoulder serving by engagement with the said jaw normally to prevent the reverse loosening movement of the 75 body and jaws on the rail.

5. A rail anchor comprising a body adapted to extend across the bottom face of a rail, jaws carried by said body and overlying the upper faces of the flanges at opposite sides of the rail, the body comprising a bearing for the bottom face of the rail located at a shorter distance from the bearing portion of one jaw on the adjacent flange than that from the bearing portion 80 of the other jaw on the flange adjacent thereto, the parts being so arranged that the device is applicable to a rail from one side thereof, and is tightened on the rail by transverse movement of the body and jaws with respect to the rail, and a wedge interposed between one of the jaws and the upper face of the adjacent flange with its thicker portion disposed adjacent to the outer edge 85 of the flange serving to increase the tightening effect upon a transverse movement of the body and the jaws with respect to the rail.

6. A rail anchor comprising a body adapted to extend across the bottom face 100 of a rail, jaws carried by said body and overlying the upper faces of the flanges at opposite sides of the rail, the body comprising a bearing for the bottom face of the rail located at a shorter distance from the bearing portion of one jaw on the adjacent flange than that from the bearing portion of the other jaw on the flange adjacent thereto, the parts being so arranged that the device is applicable to a rail from one 105 side thereof and is tightened on the rail by transverse movement of the body and jaws with respect to the rail, and a wedge interposed between one of the jaws and the upper face of the adjacent flange with its thicker portion disposed adjacent to the outer edge of the flange serving to increase the tightening effect upon a transverse movement of the body and the jaws with respect to the rail, said wedge being provided 110 with a shoulder adapted by engagement with the end of the jaw to prevent a reverse loosening movement of the body and jaws on the rail.

7. A rail anchor comprising a body adapted to extend across the bottom face of a rail, jaws carried by said body and overlying the upper faces of the flanges at opposite sides of the rail, one of said jaws being provided with clearance whereby the 125 130

anchor may be applied to a rail from one side thereof by a transverse movement thereon, the body comprising a bearing for the bottom face of the rail located at a greater distance from the point where the jaw provided with clearance has an effective bearing for applying downward pressure on the upper face of the adjacent flange than the distance from the point where the other jaw bears on the upper face of the flange adjacent thereto, and means interposed between the jaw having the clearance and the upper face of the adjacent flange serving to cause such jaw to move upwardly with respect to the upper face of the flange as the jaw moves toward the outer edge of the flange in the transverse movement for applying the anchor to the rail.

8. A rail anchor comprising a body adapted to extend across the bottom face of a rail, jaws carried by said body and overlying the upper faces of the flanges at opposite sides of the rail, the body comprising a bearing for the bottom face of the rail located between the jaws, the parts being so arranged that the device is applicable to a rail from one side thereof and is tightened thereon by transverse movement of the body and jaws with respect to the rail, and comprising a plate of sheet-metal interposed between one jaw and the upper face of the adjacent flange and provided with a shoulder in its upper face serving by engagement with the said jaw normally to prevent a reverse loosening movement of the body and the jaws on the rail, said plate having also a bearing on the outer face of the adjacent flange for holding the plate against movement inwardly with respect to the flange.

9. A rail anchor comprising a body adapted to extend across the bottom face of a rail, jaws carried by said body and overlying the upper faces of the flanges at opposite sides of the rail, the body comprising a bearing for the bottom face of

the rail located between the jaws, the parts being so arranged that the device is applicable to a rail from one side thereof, and a wedge formed of sheet-metal and having a shoulder in its upper face supported by the back-turned edge of the metal, such wedge being interposed between one of the jaws and the upper face of the adjacent flange with the thicker portion of the wedge disposed adjacent to the outer face of the flange, the arrangement being such that when the body and jaws are moved laterally with respect to the wedge and with respect to the rail into operative position on the rail, a differential action at the opposite sides of the rail serves to tighten the anchor on the rail.

10. A rail anchor comprising a body adapted to extend across the bottom face of a rail, jaws carried by said body and overlying the upper faces of the flanges at opposite sides of the rail, the body comprising a bearing for the bottom face of the rail located between the jaws, the parts being so arranged that the device is applicable to a rail from one side thereof, a wedge formed of sheet-metal and having a shoulder in its upper face supported by the back-turned edge of the metal, such wedge being interposed between one of the jaws and the upper face of the adjacent flange with the thicker portion of the wedge disposed adjacent to the outer face of the flange, and an arm formed integrally with the wedge adapted to engage the outer face of the adjacent flange for preventing movement of the wedge inwardly with respect to the flange, the arrangement being such that when the body and jaws are moved laterally with respect to the wedge and with respect to the rail into operative position on the rail, a differential action at the opposite sides of the rail serves to tighten the anchor on the rail.

WILLIAM H. DE BUSK.
